litt-Sparks Industries, Inc., Columbus, Ind., a
corporation of Indiana

Application February 5, 1940, Serial No. 317,235

1 Claim. (Cl. 155—54)

My invention relates to metal chairs of the type having generally U-shaped side members formed preferably of metal tubing and arranged so that one of the two generally parallel legs will rest on the ground or floor while the other provides an arm for the chair. It is the object of my invention to produce a chair of this general type which will support the load imposed upon it with a relatively high degree of resilience; which will be stable, especially in respect to any tendency to tip forwardly; which will be rigid except in respect to a vertically imposed load; which may be simply and economically manufactured; and which, before assembly, can be compactly packaged.

In carrying out my invention I provide for each side of the chair a resilient side member, desirably of metal tubing, formed into a general U-shape to provide a lower horizontal portion adapted to rest on the ground or floor, an intermediate, generally vertical portion, and an upper horizontal portion adapted to serve as an arm. The seat and back of the chair are conveniently formed separately, desirably as sheet-metal stampings, the rear end of the seat and the lower end of the back being secured together, the front end of the seat being attached to the intermediate portions of the side members, and the rear ends of the arm-forming portions of the side members being secured to the back at a point above the seat. The connection of the side members to the seat and to the back is of such a character as to increase the effective rigidity of the side members against distortion otherwise than in a vertical plane. An important feature of my invention resides in the shape given the intermediate portion of each side member below the seat, that portion being so shaped as to possess a relatively high degree of resilience while still joining the bottom horizontal portion of the side member at a point far enough forward to provide adequate stability of the chair against any tendency to tip forwardly.

The accompanying drawing illustrates my invention: Figs. 1 and 2 are side and front elevations respectively of a chair constructed in accordance with my invention; Fig. 3 is a fragmental side elevation of the front portion of the seat, with portions of the latter broken away to show the construction more clearly; Fig. 4 is a fragmental horizontal section on the line 4—4 of Fig. 3; Fig. 5 is a fragmental front elevation of a part of the chair-back, with portions of the back and of the associated arm broken away and appearing in section; Fig. 6 is a fragmental section on the line 6—6 of Fig. 1; and Fig. 7 is an illustra-

tion of the manner in which the parts of the chair may be arranged for packing and shipping.

The chair illustrated in the drawing comprises a seat 10 and a back 11 formed separately, desirably as sheet-metal stampings. Around its edges, the seat 10 is provided with a downwardly extending, integrally formed flange 12; and a similar flange 13, projecting rearwardly, is provided at the sides and across the top of the back 11. Bolts 14 extending through the back 11 and the flange 12 at the rear of the seat serve to hold the seat and back together.

The unit formed by the seat 10 and back 11 is supported from the ground or floor by means of two side members 16, shown as formed of metal tubing, bent to provide a lower, generally horizontal portion 17 adapted to rest on the floor or ground, and an upper horizontal portion forming an arm 18. Near each front corner of the seat 10, the flange 12 is formed, as indicated at 20, to provide a groove shaped to receive the intermediate portion of the adjacent side member 16, as is clear from Fig. 4. The flange 13, at each side of the back 11, is similarly shaped, as indicated at 21 in Fig. 5, to receive the rear end of the arm 18.

Desirably, each front corner of the chair-seat 10 is provided with a reinforcement in the form of a sheet-metal stamping 25 which lies within the flange 12 at the seat-corner and which extends for a distance in both directions from the corner along the inner face of the flange 12, being secured thereto as by spot welding. To hold the intermediate portion of each member 16 in place at the front corner of the chair-seat, two U-bolts 26 are rigidly secured to it in vertically spaced relation, the parallel legs of such bolts extending inwardly through holes in the flange 12 and/or reinforcement 25. Preferably, the U-bolts are

welded to the side members. A clip 27 (Fig. 4), provided with spaced holes for the reception of the inner end of each U-bolt 26, is held in place by nuts 28 on the threaded inner ends of the U-bolt, its intermediate portion engaging the flange 12 or reinforcement 25 opposite the member 16. When the nuts 28 are tightened, the intermediate portion of the associated member 26 is held tightly in the groove 20 and prevented from turning therein, thus serving to stiffen the intermediate portion of the member 16 against torsional stresses.

The rear end of each arm 18 and the associated grooved portion 21 of the back-flange 13 are provided with aligned holes for the reception of a bolt 30 which, when tightened, serves to

draw the arm tightly into the groove 21 and to hold it in fixed angular position relative to the back 11.

Below its point of attachment to the seat 10, each of the side members 16 is bent forwardly, as indicated at 32 in Fig. 1; and below this forwardly bent portion, the side member is formed into a smooth rearwardly-concave curve 33 joining the front end of the horizontal portion 17.

Between the two lower horizontal portions 17 of the side members 16 I provide a stretcher 35, desirably of sheet-metal, formed into a channel section and shaped at its ends to provide downwardly presented channel-like seats 36 receiving the horizontal portion 17. Bolts 37 extending through the seats 36 and the horizontal portion 17 serve to hold the stretcher in place.

Desirably, each of the horizontal portions 17, at the point where it is attached to the stretcher 35, is bent downwardly as indicated in Fig. 1, so that each portion 17 engages the supporting surface upon which it rests only at spaced points 39 and 40. This arrangement not only provides for stability of the chair should the supporting surface be uneven in character, but it also provides clearance for the lower ends of the bolts 37.

The stability of the chair against forward tipping will depend upon the fore-and-aft disposition of the points 39 relative to the chair-seat 10. Specifically, the farther forward the points 39 are, the greater the resistance of the chair to forward tipping. It will be obvious that, for any given position of the points 39, the provision of the forwardly-bent portion 32 of each side member 16 makes it possible to increase both the radius and the angular extent of the bend 33. In other words, if the forward bend 32 were absent and if the bend 33 were on the same radius as is illustrated in Fig. 1, the bend 33 would have a smaller angular extent, and the point 39 would be farther to the rear than it actually is. Shortening the angular extent of the bend 33 would decrease the resilience of the chair under vertically applied loads, and rearward movement of the points 39 would decrease the stability of the chair against forward tipping. It is thus seen that by providing the forward bend 32, I am enabled to increase both the resilience of the members 16 and the stability of the chair against forward tipping.

Because of the manner in which the side walls 16 are connected to the seat 10, the back 11, and the stretcher 35, the chair is relatively rigid to horizontally applied forces. That is, since the

grooves 21 in the chair-back and the seats 36 at the end of the stretcher have a considerable extent along each side member, they tend to hold each side member in fixed angular position relative to the back 11 and the stretcher 35; while the U-bolts 26, rigid with each side member 16 at the points where it engages the seat, prevent the side member from being twisted at such point. As a result, the back 11 of the chair can not be moved laterally for any appreciable distance relative to the rear ends of the horizontal portions 17 of the side members.

For the sake of appearance, and also to provide some stiffening effect, the back of the chair 15 illustrated in the drawing is formed with forwardly offset panels, shown as three in number, separated by vertically-extending, forwardly opening channels 45. The chair-seat, which is desirably of "saddle" conformation, may be 20 formed with two upwardly opening channels 46 which communicate with the channels 45 in the chair back and which project a short distance forwardly therefrom. With the seat arranged to slope rearwardly, as is preferable for 25 greatest comfort, the channels 46 and 45 provide a path for the escape of water.

The side members 16, seat 10, and back 11 are so proportioned that when disassembled they may be arranged as indicated in Fig. 7, with the seat 30 and back received between the upper and lower portions 18 and 17 of the side members. This greatly facilitates packing of the disassembled chair for shipment, as any carton large enough to receive the side members will also receive the 35 remaining portions of the chair. The stretcher 35, being small, may be placed in such a carton in any of a variety of positions.

I claim as my invention:

In a chair having a seat and back, side members 40 for supporting said seat and back from a supporting surface, each of said side members being formed of resilient metal tubing of circular cross-section and comprising a generally horizontal portion adapted to rest on the supporting 45 surface and a second portion rising from the front end of said horizontal portion to said seat, said seat being provided with a downwardly extending flange overlapping the second portion of each side member, and a U-bolt embracing and 50 welded to said side member, projecting laterally therefrom, and extending through said flange, said flange being formed with a groove for the reception of the side member.

EARL C. BOOTH.
